UNITED STATES PATENT OFFICE.

JOHN AMMON, OF NEW YORK, N. Y., ASSIGNOR TO WESSELL, NICKEL & GROSS, OF SAME PLACE.

PIANO-FORTE DAMPER-FRAME.

SPECIFICATION forming part of Letters Patent No. 236,291, dated January 4, 1881.
Application filed May 31, 1880. (No model.)

To all whom it may concern:

Be it known that I, JOHN AMMON, of the city of New York, in the county and State of New York, have invented a certain new and 5 useful Improvement in Piano-Forte Dampers, of which the following is a specification.

The object of my invention is to provide in a horizontal piano for adjusting all the dampers separately relatively to the damper-frame, so 10 that when said frame is raised by the loud-pedal the dampers are all lifted away from the strings simultaneously, and not one before another, as would be liable where there is no means of independently adjusting said damp- 15 ers.

To this end the invention consists in the combination, in a horizontal piano, with a series of dampers, and a damper-frame to which all the damper-levers are hinged and by 20 which they are raised, and which is provided upon its upper surface with a bearing-surface for said damper-levers, of an adjusting-screw between each damper-lever and said bearing-surface, whereby provision is afforded for ad- 25 justing the dampers relatively to the frame and independently of each other, so that when lifted they will all leave the strings at exactly the same time.

In the accompanying drawings, Figure 1 30 represents an end view of a damper-frame and a side view of a damper and appurtenances embodying my invention. Fig. 2 represents a plan of a portion of such damper-frame, a damper, and string; and Fig. 3 represents a 35 transverse section of the damper-frame and a side view of a damper-lever having my invention applied thereto.

Similar letters of reference designate corresponding parts in all the figures. 40 D designates the damper-frame, into which all the levers B, carrying dampers C, are pivoted, as at a, in the usual manner, and which is itself pivoted, as at b, in the manner customary in horizontal piano-fortes, and provided 45 at each end with the usual set-screw c, for adjusting it, and so regulating all the dampers together. A designates one of the strings. Upon the upper surface of the frame D is a bearing-surface, D', for all the damper-levers 50 B; and when the frame is lifted by the loud-pedal the said bearing-surface of the frame,

acting upon the levers B, raises all the dampers C away from the strings.

In case any of the damper-levers become warped, so that individual adjustment is necessary, it can only be accomplished in the ordinary construction of piano-forte actions by building up with cloth under the lever or paring away the lever at the part which rests upon the cloth. This, of course, is tedious, 55 and can only be done by means of tools. In order to provide a convenient means for effecting such adjustment I employ, in connection with each damper-lever, a regulating-screw, d, placed between the lever and the 60 bearing-surface on the damper-frame, and forming an adjustable stop to the downward movement of the said lever. In the present example of my invention these screws are inserted through and move with the levers, and 70 are furnished with felt-covered tips or buttons e, which impinge against the damper-frame; but they might, if desirable, be inserted through the damper-frame, and in this case the levers would strike upon them in their 75 fall.

It will be seen that by my invention, in addition to the means ordinarily employed for adjusting the damper-frame with all the attached dampers, I provide a means whereby 80 each damper may be conveniently adjusted independently of all the others, and without the use of any tools or appliances, as the regulating-screws may be easily turned by hand.

What I claim as my invention, and desire 85 to secure by Letters Patent, is—

The combination, in a horizontal piano with a series of dampers and a damper-frame, to which all the damper-levers are hinged, and by which they are raised, and which is provided upon its upper surface with a bearing-surface for said damper-levers, of an adjusting-screw between each damper-lever and said bearing-surface, whereby provision is afforded for adjusting any of the dampers relatively to 90 the frame and independently of each other, substantially as specified.

JOHN AMMON.
